MITER BOX

Wilfred A. Larson, New Britain, Conn., assignor
to The Stanley Works, New Britain, Conn., a
corporation of Connecticut

Application December 6, 1939, Serial No. 307,852

3 Claims. (Cl. 143—89)

The present invention relates to miter boxes and has for its object an improved device of this character in which the saw guide means and swivel means therefor are positioned above the sawing table and readily adjustable relative thereto.

A still further object of the present invention is to provide an improved device of this character, which is simple in construction and wherein most of the parts thereof may be stamped from heavy gauge metal to provide a device which is capable of withstanding the hard usage to which such devices are subjected, but which is extremely inexpensive to manufacture.

Other objects will be in part obvious and in part pointed out more in detail hereinafter.

The invention accordingly consists in the features of construction, combination of elements, and arrangement of parts, which will be exemplified in the construction hereafter set forth and the scope of the application of which will be indicated in the claims.

In the accompanying drawings:

Figure 1 is a perspective view of a miter box embodying the invention herein;

Fig. 2 is an end view partly in section of the embodiment shown in Fig. 1; and

Fig. 3 is a fragmentary rear view partly in section of the embodiment shown in Fig. 1.

Referring to the drawings, the miter box includes a rectangular sawing table 10 which is shown as being made of wood to allow its being renewed when desired. Secured to the rear edge of the table 10 by suitable screws 12 is a back plate 14 comprising a pair of vertically arranged members 16 and 18. The members 16 and 18 are so secured that their inner vertical edges 20 and 22 are spaced apart to provide a saw slot 24.

The positioning member 14 also has stamped out therefrom adjacent the vertical edge 20 a depending guide lug 26 which is offset rearwardly but parallel to the plane thereof by an angular portion 28. There is arranged in vertical alignment, and preferably above the guide lug 26, a bolt receiving aperture 30 adapted to receive a securing bolt 32. The bolt 32 is provided with a mushroom head 34, non-circular neck 36, too large to pass through the aperture 30, and a threaded shank 38 adapted to have threaded thereon a suitable securing nut 40.

The lug 36 and securing bolt 32 cooperate to guide and adjustably mount a relatively narrow vertically extending leg 42 on the rear face of the member 16. The leg 42 has cut therein a

centrally arranged, vertically extending, elongated slot 44 having approximately the same width as the guide lug 26 and non-circular neck 36 of the securing bolt 32.

With this arrangement, when the parts are assembled, the non-circular neck 36 of the securing bolt and the securing lug 26 position and guide the leg 42 vertically. The non-circular neck also prevents the turning of the bolt upon rotation of the nut 40 to secure the leg in its adjusted position.

The leg 42 has the upper end thereof bent forwardly through ninety degrees to provide a support for the arm 48 of a horizontally arranged indexing plate 50. The arm 48 is secured to the bracket 46 by spot welding, and to add rigidity to the structure it may have a downwardly depending portion 52 welded to the rear face of the leg 42.

The arm 48 extends laterally from the bracket 46 so as to position the indexing plate 50 in overhanging alignment with the saw slot 24. The indexing plate 50 is substantially circular and includes a raised center portion 54 and outer peripheral flange 56. The raised central portion 54 has a centrally located aperture 58 therethrough, which aperture is also centrally located relative to a vertical plane an equal distance between the edges 20 and 22 of the saw slot 24 and in alignment with a zero indexing pointer 60 on the forward edge of the peripheral flange 56.

The aperture 58 is adapted to receive a swivel pin 62 comprising a threaded shank 64, collar 66, and handle portion 68; the handle portion being bent at right angles to the shank to allow ready manipulation of same. The shank 64 is adapted to extend through the aperture 58 with the collar 66 resting on the top surface of the indexing member, and the threaded shank extends beneath the downwardly facing undersurface 70 of the peripheral flange 56.

The pivot pin 62 serves to cooperatively support and position a swivel plate 72 relative to the indexing plate 50. The swivel plate 72 is of greater outside diameter than the peripheral flange 56 of the indexing plate, and there is provided a centrally arranged aperture 74 in which there is secured a threaded clinch nut 76 having a threaded bore 78 therethrough, which bore is centrally located relative to the periphery of the swivel plate 72. The threaded bore 78 is adapted to receive the shank 64 of the pivot pin 62, whereby the swivel plate may be moved into and out of abutting engagement with the bottom

surface 70 of the peripheral flange 56 of the indexing plate.

When so positioned, the portion of the swivel plate which extends outside of the peripheral flange 56 provides a ring portion on which there may be provided a series of graduations for angularly adjusting the swivel plate relative to the indexing plate. In the embodiment illustrated, these graduations extend fifty degrees in either direction from a common zero point. Obviously, in order to adjust the swivel plate 72, it is only necessary to slack off on the pivot pin 62, whereupon the plate may be rotated to a new angular position, and then, by holding the plate, the pivot pin may be rotated to secure it in its adjusted position.

The swivel plate 72 has integrally formed therewith the saw guide means which comprise a pair of spaced apart, parallel, substantially square plate members 80 and 82; each plate having an upper portion 84, an intermediate inwardly tapering portion 86, and a lower portion 88. The upper portions 84 may have formed therein rearwardly of the vertical center line of the plates substantially inverted conical sections 90 provided with outwardly projecting peripheral flanges 92 adapted to be secured to the under surface of the swivel plate 72, thus spacing the greater portion of the guide means forwardly of the back plate 14.

As best seen in Fig. 3, the upper portions of the plates have a relatively large spacing therebetween, and the forward edges thereof are cut on a bias 94 extending from the swivel plate to adjacent the forward upper edge of the tapering portion 86, whereby a saw may readily be placed within the guide means. However, the inwardly tapering intermediate portion 86 positions the lower portions 88 in substantially closed alignment so that the width therebetween is slightly less than the thickness of the saw, whereby when the saw is placed within the guide it will be engaged by the lower portions 88. As the plate members are of substantial length, there is sufficient resiliency in the metal to allow the lower portions 88 to be sprung slightly to permit the placing of the saw therebetween.

From the foregoing, it can be readily seen that the saw guide means may be readily adjusted to accommodate various thicknesses of wood by simply slackening off the securing nut 40, whereupon the raising and lowering of the leg 42 will simultaneously adjust the saw guide means therewith. Likewise, in order to angularly adjust the saw guide means, it is only necessary to slack off on the swivel pin 62, set the swivel plate to the proper angle, and then take up on the swivel pin.

It is also apparent from the foregoing that, with the exception of the securing bolt and swivel pin, the various metal parts of the miter box may all be stamped from a suitable heavy gauge material and, when necessary, bent into the form shown. The various stampings may all be strengthened by the provision of suitable flutes or ribs readily seen in the drawings, but which have not been described inasmuch as they

merely add strength to the structure. However, by so manufacturing the parts, the device may be inexpensively manufactured and yet sufficiently rugged to stand the hard usage to which such devices are subjected and also be accurate in its settings.

If desired, there may also be provided on the forward edge of the sawing table 10, suitable stop lugs 96 pivotally secured thereto by screws 98, whereby the stops may be turned downwardly to engage the edge of a bench to steady the miter box during cutting operations.

I claim as my invention:

1. In combination with a miter box, a horizontally arranged indexing plate having a flat peripheral flange and a raised central portion provided with a centrally located aperture, saw guide means underlying the indexing plate and comprising a circular swivel plate having a centrally arranged threaded opening and a pair of complementary parallel plate members depending from said swivel plate, said plate members each including an upper and a lower portion, said upper portions being spaced apart to permit the ready insertion of a saw therebetween and having their upper edges secured to the bottom of the swivel plate, and the lower portions of said plate members being closely aligned to clamp the sides of a saw when inserted therebetween, and a single pivot pin pivotally mounted in the opening in said index plate and having its lower end threaded and received within the threaded opening of the swivel plate, whereby upon rotation of the pivot pin said swivel plate may be adjusted relative to and secured against the flange of the index plate.

2. In combination with a miter box, a horizontally arranged index plate having a flat peripheral flange and provided with a centrally located aperture, saw guide means underlying the indexing plate and comprising a circular plate having a centrally arranged threaded opening, and a pair of complementary parallel plate members depending from said swivel plate and having their upper edges secured to the swivel plate, and a single pivot pin pivotally mounted in the opening in said index plate and having its lower end threaded and received within the threaded opening of said swivel plate, whereby upon rotation of the pivot pin said swivel plate may be adjusted relative to and secured against the flange of the index plate.

3. In combination with a miter box, an index plate, saw guide means pivoted thereon, said saw guide means comprising a circular swivel plate and a pair of complementary parallel plate members depending from said swivel plate, said plate members each including an upper portion and a lower portion, the upper portions having an inverted conical section terminating at its upper edge in a lateral flange secured to the swivel plate and spaced apart to permit the ready insertion of a saw therebetween, and the lower portions of said plate members being closely aligned to clamp the sides of a saw therebetween.

WILFRED A. LARSON.
